CHARLES T. FABER, OF NEW YORK, N. Y.

Letters Patent No. 69,329, dated October 1, 1867.

IMPROVED SELF-ADJUSTING LID-SUPPORT FOR PIANOS DESKS, &c.

The Schedule referred to in these Letters Patent and making part of the same.

TO ALL WHOM IT MAY CONCERN:

Be it known that I, CHARLES T. FABER, of the city, county, and State of New York, have invented a new and useful improvement in Self-Adjusting Lid-Supports; and I do hereby declare that the following is a full and exact description thereof, reference being had to the accompanying drawings, making a part of this specification.

The object of my invention is to provide a prop or support to lids or covers of pianos, desks, boxes, &c., which will be automatic in its action, so that such lid may be raised and held, or lowered without the necessity of touching said prop or support, as will be hereinafter explained.

In the accompanying drawing, B represents a desk with my improved prop or support applied, said prop consisting of a brace made tapering in the usual or any desired form, having its larger end attached to the side of the desk or other convenient point by means of a screw-pivot, upon which it is free to turn, as hereinafter explained. To prevent the pivot from working and becoming loose in soft wood, a perforated metal plate, shown at M, may be inlaid in or otherwise secured to the surface to which said prop is attached, between the end of the prop and said surface. In the end of the prop a slot or incision is formed or cut, wide enough to allow it to receive a metal hook, and allow it to move freely therein, as shown at L in the drawing. A spring of metal, or any elastic band, is attached at one end to this hook, and at its other end to the side of the piano, desk, or other article of furniture to which the prop is applied. By this arrangement it will be seen that when the lid is raised the elasticity of the spring acting upon the prop will cause its free end to rise with and slide along the lid until it reaches a notch formed therein, into which said free end falls, and being prevented thereby from returning, is made to properly support the elevated lid. To now enable the lid to be lowered without touching the brace or prop, a small latch or lever, which I call the adjuster, made of any suitable material, as wood or metal, shown at I J K of the drawings, is pivoted in a groove in the lid, at the back or foot of the notch into which the prop falls, in such manner as to swing freely as the lid is raised or lowered.

The operation of this adjuster is as follows: When the lid is raised and the prop falls into the notch in the lid, the adjuster hangs suspended from its pivot in a vertical position behind the prop. The lid is now slightly raised, when the continued backward movement of the free end of the prop throws the adjuster against the lid until it has passed over it, when the adjuster again drops into a vertical position in front of the lever, when, by lowering the lid, the adjuster is thrown forward over the notch, and is of sufficient length to form a bridge over said notch, over which the free end of the prop slides as the downward movement of the lid is continued, in a manner that will be readily understood from the drawings. When the prop has passed the notch and the adjuster thus bridging it, the adjuster again falls, by its own gravity, into its former vertical position, and is ready for a repetition of the operation above described. Any desired number of notches and adjusters may be applied to the lid, so that any desired degree of elevation may be given thereto. The adjuster, instead of being pivoted in a groove in the lid, may be applied to a small slotted metal plate let into the lid, or in any suitable manner.

A modification of the above manner of applying my improvement is shown at A, representing a piano to which the prop is attached in such manner as to dispense with the spring above described. In this instance the prop is pivoted at its larger end to the lid, through the medium of a metal hinge or plate, or in other suitable manner, while the opposite free end, falling by its own gravity, is allowed, as the lid is raised or lowered, to slide on a ledge of wood or metal attached to the side of the piano or desk to which it is applied, as shown at Figures C and D of the drawing. A notch is formed in the ledge, into which the free end of the prop falls as the lid is raised, which prevents the return movement of the prop, and causes it to hold the lid in its elevated position. At the rear of the notch in the ledge the adjuster is pivoted, at or near its lower end, and has its lower end weighted in such manner as to maintain the position shown at Fig. C, and I, Figure E. When it is desired to lower the lid it is first raised slightly, so as to cause the prop to slide by the adjuster, as shown at C, when the lowering of the lid and the consequent forward movement of the slide throw the adjuster forward and cause it to bridge the notch in the manner shown at Fig. D, thereby leaving the lid free to be lowered without any necessity for touching the prop. In this construction, as in that before described, any desired number

of notches may be formed in the ledge for regulating the degree of adjustment of the lid or cover, and a corresponding number of "adjusters" applied thereto.

Having now described the construction and operation of my invention, what I claim, and desire to secure by Letters Patent, is—

The adjuster for bridging the notch or stop which holds the prop or support for the lids of pianos, desks, and other similar articles of furniture, made automatic in its action by means substantially as described.
